UNITED STATES PATENT OFFICE.

HORACE C. WILCOX, OF WEST MERIDEN, CONNECTICUT, ASSIGNOR TO THE
MERIDEN BRITANNIA COMPANY, OF SAME PLACE.

IMPROVEMENT IN TABLE-CUTLERY.

Specification forming part of Letters Patent No. 150,382, dated April 28, 1874; application filed
March 26, 1874.

To all whom it may concern:

Be it known that I, HORACE C. WILCOX, of West Meriden, in the county of New Haven and State of Connecticut, have invented a new Improvement in Table-Cutlery; and I do hereby declare the following, when taken in connection with the accompanying drawing and the letters of reference marked thereon, to be a full, clear, and exact description of the same, and which said drawing constitutes part of this specification, and represents a side view of a table-knife.

This invention relates to an improvement in finishing the handles of that class of table-cutlery in which the handle, bolster, and blade are made in one piece, the object being to give a matted or granulated appearance to the handle, whereby the handle is more conveniently and comfortably held in the hand; and the invention consists in giving to the handle a "sand-blast" finish before it is electroplated.

I represent only a knife, but it will be understood that other articles of table-cutlery are included.

The blade A, bolster B, and handle C are formed together in one and the same piece by the usual process of forging, and then ground, as usual. I then submit the handle C to a strong sand-blast, which forms a sharp matted surface, and having the appearance as shown in the drawing. This takes away the usual smoothness of this class of handles, which renders them difficult to handle and gives to the handle a comfortable and pleasant feeling in the hand, and enables the person to hold the knife firmly.

I claim as my invention—

As an article of manufacture, table-cutlery in which the handle, bolster, and blade are in one and the same piece of steel and the handle cut or matted by sand-blast, substantially as described.

HORACE C. WILCOX.
